UNITED STATES PATENT OFFICE.

GEORGE T. WHEELER, OF MEXICO, NEW YORK, ASSIGNOR OF SEVEN-NINTHS TO WILLIAM S. LANSING AND J. FITCH LANSING, OF SAME PLACE, AND DAYTON R. FRITTS, OF PARISH, NEW YORK.

DESIGN FOR A CREAM-SEPARATOR.

SPECIFICATION forming part of Design No. 29,715, dated November 22, 1898.

Application filed October 31, 1898. Serial No. 695,137. Term of patent 14 years.

To all whom it may concern:

Be it known that I, GEORGE T. WHEELER, a citizen of the United States, and a resident of the town of Mexico, in the county of Oswego, in the State of New York, have invented and produced a new and original Design for a Cream-Separator, of which the following, taken in connection with the accompanying drawings, is a full, clear, and exact description.

In the accompanying drawings, Figure 1 is a front view of a cream-separator, showing my design; and Fig. 2 is a vertical transverse sectional view taken on the line X X of Fig. 1.

As shown in the drawings, the leading or material features of my design consist of the cylinder A, the diaphragm d, disposed some distance above the base of the cylinder and

inclined to the front thereof and having the indentation a in its lowest portion and an aperture b in said indentation, the bead c, extending around the interior of the cylinder in a line following the edges of the diaphragm and even therewith, and the orifice e in the front of the cylinder and beneath the aforesaid diaphragm.

Having described my invention, what I claim as new, and desire to secure by Letters Patent, is—

The design for a cream-separator as herein shown and described.

GEORGE T. WHEELER. [L. S.]
